UNITED STATES PATENT OFFICE.

RAY A. McHALE, OF SYRACUSE, NEW YORK, ASSIGNOR TO LOIS T. McHALE, OF SYRACUSE, NEW YORK.

TIE BRACE FOR CONCRETE FORMS.

Application filed January 4, 1921. Serial No. 424,988.

To all whom it may concern:

Be it known that I, RAY A. McHALE, a citizen of the United States, and a resident of Syracuse, in the county of Onondaga and State of New York, have invented a certain new and useful Tie Brace for Concrete Forms, of which the following is a specification.

This invention has for its object a tie brace for holding the opposing walls of concrete forms in position or in parallelism to each other, which tie brace is particularly simple and economical in construction, readily placed in position and in which the parts thereof, not left in the concrete wall, are readily removed, and further which is highly efficient and durable in use. The invention consists in the novel features and in the combinations and constructions hereinafter set forth and claimed.

In describing this invention, reference is had to the accompanying drawings in which like characters designate corresponding parts in all the views.

Figure 1 is a vertical sectional view of this tie brace, the contiguous part or walls of the form being shown.

Figure 2 is a plan view of parts seen in Fig. 1.

Figures 3 and 4 are respectively an end view and an enlarged sectional view of one of the blocks or sleeves of this brace.

Figure 5 is a perspective view of the tightening wedge.

This tie brace comprises generally, opposing blocks or sleeves designed to lie against the inner opposing faces of the walls of the forms, the blocks being formed with internal cavities having key slots in their opposing ends, a tie rod having angular or laterally turned ends which are movable through the key slots and into interlocking engagement with the end walls of the cavities of the block by relative endwise and turning movements of the tie rod and the blocks, and means extending through the walls of the form for pulling the blocks outwardly against the inner faces of the form. Preferably, this means includes pull rods which interlock with the blocks in a manner similar to that in which the tie rods interlock with the blocks.

1 designates the blocks which are here shown as conical in form with their larger ends or bases disposed outwardly in order

to lie against the inner opposing faces 2 of the forms 3, each block being provided with an internal cavity 4 having end walls 5, 6 which are formed with openings for the tie rod 7 and the tension rods 8. As here shown, preferably, the openings in each of the walls 5, 6 is in the form of, what, for convenience, is called a keyhole or slot 9 or 10, that is, a slot extending substantially radially of the end wall of the block; and, in order to permit a hook to be inserted therethrough and turned to interlock with the end wall, the tie rod 7 is provided with angular or laterally turned hook ends 11 for entering the slots 9 upon relative endwise movement of the rod 7 and the blocks 1 and to interlock with the opposing end walls of the blocks upon a relative turning movement of the rod to the blocks. The rods 8 are provided with similar hooks 12 at their inner ends arranged to interlock with the end walls of the cavity on the outer sides of the block by similar movements. Each block 1 is preferably provided with a partition as an internal annular flange 13 intermediate the ends thereof for spacing the ends of the rods 7, 8.

The rods 8 are drawn endwise by a particularly simple and cheaply constructed wedge 13 which as seen in Fig. 4 is U-shaped in cross section, the wedge being arranged astride the bill 14 of the hook at the outer end of each rod 8, the bill 14 of the hook being substantially parallel to the major part of the rod 8.

When the wedge is arranged astride the bill 14, the intermediate or back 15 thereof presses against the framing of the form and the inclined edge 16 of one of the bifurcations of the wedge presses against the bend of the hook. By this construction of wedge no metal bearing member is necessary for the wedge. Also the wedges are very readily placed in position and removed. The forms usually have upright frame members 17 and lengthwise frame members 18. The rods 18 extend through the walls of the form and through the frame members 18 and the wedges bear directly against these members 18 instead of against metal bearing plates especially provided for the members.

Owing to the arrangement by which the interlocking of the tie rods and tension or pull on rods with the blocks or inserts 4 is

effected, this brace is readily placed in position when the concrete is set the wedges, pull rods and blocks are readily removed. Furthermore, owing to this construction, and to the wedge construction the whole device consists of but few parts which are particularly economical in construction.

In use, after the concrete wall is hardened the tension rods 8 can be readily removed upon knocking out of the wedges 13 and removing the rods 8 by a partial turning and endwise movement thereof. Thereafter, the walls of the form are removed, the blocks or inserts 10 displaced and the holes left therein filled up with cement.

What I claim is:

1. In a tie brace for concrete forms, the combination of a pair of blocks each formed with a cavity having a slotted opening at its end wall, a tie rod having laterally turned hook shaped ends for interlocking in the cavities of the blocks by relative endwise and turning movements of the blocks and the tie rods to pass the hooks through the slotted openings and to engage the hook-shaped ends with the inner faces of the end walls of the cavities, and means for tightening the blocks in position, substantially as and for the purpose described.

2. In a tie brace for concrete forms, the combination of a pair of blocks, each formed with a cavity having a key slot in one end wall, a tie rod having laterally turned hook shaped ends arranged to enter the slots in the opposing walls of the blocks and interlock therewith in the recess by a relative endwise and turning movement of the blocks and the tie rods, tension rods and having hooks at their inner ends arranged to interlock in the cavities of the blocks through the outer end walls thereof, and means for drawing the last mentioned rods outwardly, substantially as and for the purpose set forth.

3. In a tie brace for concrete forms, the combination of a pair of blocks each formed with a cavity having key slots at their ends, a tie rod having laterally turned hook shaped ends arranged to enter the slots in the opposing ends of the blocks and interlock in the cavities thereof by a relative rotation of the blocks and the tie rod, rods having hooks at their inner ends arranged to interlock in the cavities of the blocks through the key slots in the outer ends of the block, and means for drawing the last mentioned rods outwardly, substantially as and for the purpose specified.

4. In a tie brace for concrete forms, the combination of a pair of blocks, each formed with a cavity having openings at its end walls, a tie rod arranged to interlock at its ends in the cavities of the block by a relative endwise and turning movement of the

rod and the blocks, additional rods arranged end to end with the tie rod and having means at their inner ends arranged to interlock in the cavities of the blocks respectively by relative endwise and rotary movement of such rods and the blocks, and means for tightening the last mentioned rods, substantially as and for the purpose set forth.

5. In a tie brace for concrete forms, the combination of a pair of blocks, each formed with a cavity and with a key slot at the outer end of the cavity, a tie rod connecting the blocks, and rods arranged in alignment with the ends of the tie rod and having hooks at their inner ends arranged to interlock in the cavity of the block through the key slots by relative endwise and rotary movement of the rods and the blocks, substantially as and for the purpose described.

6. In combination with a concrete form of a tie brace comprising blocks arranged against opposing inner faces of the forms, a tie rod connecting the blocks, rods interlocked with the blocks and extending through the walls of the form to the outside thereof and formed with a hook having the bill thereof arranged substantially parallel to the rod, and a wedge U-shaped in cross-section arranged astride the bill of the hook with its intermediate part bearing against the form, substantially as and for the purpose described.

7. In a tie brace for concrete forms, the combination of a form, a pair of blocks bearing against inner opposing faces of the form and each having an internal cavity formed with key slots in the end walls thereof, a tie rod having laterally turned hook shaped ends arranged to enter the key slots and interlocked with the walls of the cavities of the blocks by relative endwise and rotary movements of the tie rod and the blocks, pull rods extending through the walls of the form and having laterally turned hooks at its inner ends arranged to interlock in the cavities of the blocks through the key slots in the outer end walls of the cavities of the block by relative endwise and rotary movements of the blocks in the pull rods, the pull rods being formed with hooks at their outer ends having their bills arranged substantially parallel to such rods, and U-shaped wedges arranged astride the bills of the last mentioned hooks with one inclined surface of each wedge bearing against the bend of the contiguous and the intermediate or back of the U-shaped formation against the form, substantially as and for the purpose described.

In testimony whereof, I have hereunto signed my name, at Syracuse, in the county of Onondaga and State of New York, this 30th day of November, 1920.

RAY A. McHALE.
